UNITED STATES PATENT OFFICE.

PERCY B. CAMP, OF MAYWOOD, ILLINOIS, ASSIGNOR TO UNIVERSAL DRAFT GEAR ATTACHMENT CO., A CORPORATION OF ILLINOIS.

BRAKE MECHANISM.

Application filed February 2, 1925. Serial No. 6,199.

This invention relates to brakes, and more particularly to brake operating mechanism.

One of the objects of the invention is the provision of new and improved brake operating mechanism that, during its initial movement, will rapidly take up the slack in the mechanism and that on its final movement will have increased leverage for applying the brakes.

Another object of the invention is the provision of a sectional brake staff that is provided with new and improved mechanism for causing the sections to move together during the initial turning of the staff, but which will automatically shift the mechanism whereby one section of the shaft may be rotated relatively to the other, thereby increasing the leverage in the final turning of the staff in applying the brakes.

A still further object of the invention is the provision of new and improved means for applying brake mechanism that is self-locking in operation.

Other and further objects and advantages of the invention will appear from the following description taken in connection with the accompanying drawings, in which

Fig. 1 is a side elevation of a portion of a railway car showing my invention in position thereon;

Fig. 2 is a section on line 2—2 of Figs. 1;

Fig. 3 is a side elevation of the differential gear mechanism with parts in section and parts broken away;

Fig. 4 is a section on line 4—4 of Fig. 3;

Fig. 5 is an elevational view of a detail; and

Fig. 6 is a perspective view of another detail of the invention.

On the drawings, the reference character 8 designates a railway car, on one end of which is mounted a platform 9 and a brake staff 10 comprising the upper and lower sections 11 and 12. The upper section is provided with a lever or hand wheel 13 for manually rotating the shaft, as is usual in such constructions. A conical drum 14 is mounted on the lower section 12 of the shaft. A flexible member, as the cable 16, is adapted to be wound on the drum 14 for operating the brake operating mechanism. The brake operating mechanism may be of any suitable form. In the form disclosed in the drawings the mechanism comprises a lever in the form of an eccentrically mounted sheave 17. The lever

is pivoted in the bifurcated end of a brake rod 18 which is connected to the brake lever in the usual manner. The cable 16 is led around the sheave 17 and has its opposite end attached to the anchor member 19. The cable 16 is attached to the sheave as at 21 whereby when the drum 14 is rotated it will cause rotation of the sheave 17. The parts are so arranged that during the initial turning of the brake staff the cable will be wound on the larger portion of the drum and will operate on the short end of the lever or sheave 17 whereby the slack will be taken up very rapidly. During the final movement of the staff the cable will wind about the smaller portion of the conical drum 14 and will at the same time be operating on the long arm of the lever 17 whereby great power is applied to the brake rod for setting the brakes.

It is desirable that mechanism be provided for connecting the two sections of the brake staff, whereby during the initial turning of the wheel 13 the two sections will turn together, but as soon as the setting of the brakes offers a predetermined resistance to the winding of the cable 16 on the drum 14 the connecting mechanism will be shifted automatically and the drum 14 will rotate at a slower rate of speed than the wheel 13, thereby greatly increasing the leverage in setting the brakes. A suitable gear mechanism employed for this purpose will now be described.

In the form of the device selected to illustrate one embodiment of the invention the mechanism comprises a casing 22 which is composed of an upper section 23 and a lower section 24. The lower section 24 of the casing 22 has its central portion depressed, that is, the section is cup-shaped. The upper portion of the lower section is provided with an annular laterally extending flange 25 which is adapted to be engaged on its under side by rollers 26 on the upper section of the casing for holding the two sections assembled. The section 24 is provided with a depending hub 27 through which the lower section 12 of the brake staff is adapted to extend and rotate therein.

Suitable means are provided for connecting the two sections of the brake staff together. As shown, a differential gear mechanism is employed for this purpose. The mechanism comprises a spider 28 non-rotatably mounted on the upper end of the staff section 12 in any approved manner, as by

providing an angular recess in the hub portion 31 of the spider in which the upper angular end 32 of the staff section 12 is adapted to engage. The spider is in the form of a 5 plate having its central portion depressed. The plate is provided with an opening at each end thereof across which extend spindles 33 carried by said spider and on which are journaled the pinions 34 and 35. The pinion 34 10 meshes with a circular rack 36 on the upper section 23 of the casing and the pinion 35 meshes with the circular rack 37 on the lower section of the casing. The two pinions 34 and 35 are rigidly connected together. The 15 pinion 34 is considerably larger than the pinion 35. The rack 36 may also contain fewer teeth than the rack 37 whereby a differential movement may be obtained between the upper section of the casing and the section 20 11 of the brake staff, as will presently appear.

Means for causing the lower section 12 of the brake staff to turn with the upper section 11 will now be described. A disk 38 having inclined ratchet teeth 39 on its upper surface is slidably mounted on the lower angular end 41 of the upper section 11 of the brake staff. The disk 38 is non-rotatably mounted on the end 41 as by being provided with an angular hole through which the end 30 41 extends. The spider 28 is provided with upstanding lugs 42 to which a pawl 43 is pivotally connected. The pawl is adapted to engage the inclined teeth 39 thereby causing the spider to turn as the hand wheel 13 is turned. The pawl is weighted at its outer 35 end which will hold the pawl in engagement with the teeth 39 during the initial turning movement of the brake staff. The teeth are so inclined and the pawl so arranged that 40 the pawl will tend to ride over the teeth during the final turning movement of wheel 13 in applying the brakes. In applying the brakes, when the resistance to the turning movement of the lower section 12 of the staff 45 reaches a predetermined amount, as when the brakes engage the wheels, the pawl 43 will slip over the inclined teeth 39 and other means are necessary to cause the parts to operate to apply the brakes.

50 The final turning movement of the brake staff is accomplished through the disk 44 which is provided on its upper surface with ratchet teeth 45 that are engaged by a pawl 46 mounted on the upper section 23 of the casing. The disk 44 is rigidly connected to the staff section 11.

In the operation of the device, assuming that the brakes are in off position, the wheel 13 is turned clockwise which will carry the 60 disks 38 and 44 also clockwise. The pawl 43 engaging the teeth 39 of the disk 38 will carry the spider 28 in the same direction, and at the same speed as the wheel 13. Since the spider is fixed on the section 12 of the 65 lower section, that section will move at the

same rate of speed as the upper section of the staff. During this initial turning movement of the wheel the cable 16 will be wound on the larger diameter of the conical drum 14 and the cable acting on the short arm of the 70 lever 17 will cause the long arm of said lever to rapidly take up the slack in the brake operating mechanism. In other words, the two sections 11 and 12 will move as a single rod in taking up the slack. The fact that the 75 engagement of the pinions 34 and 35 with the racks 36 and 37 will cause the casing 23 to overrun is immaterial since the pawl 46 which is mounted on the casing 23 will ride over the teeth 44 as is usual in pawl and 80 ratchet construction and permit the upper casing section 23 to rotate faster than the staff sections 11 and 12.

When the resistance to the rotation of the lower section 12 reaches a predetermined 85 amount, as when the brake shoes engage the wheels, the pawl 43 will ride up over the ratchet teeth of the disk 38 whereupon the casing 23 and spider 28 will no longer be rotated by said pawl. At this instant the pawl 90 46 will engage the ratchet teeth 45 as the latter are rotated, thereby causing the casing 23 to turn at the same rate of speed as the wheel 13. Further turning movement of the wheel 13 will rotate the shaft section 12 95 through the differential gearing at a reduced rate of speed whereby an increase of leverage is available for setting the brakes. The ratio of rotation between the shaft sections 11 and 12 may be varied by varying the ratio of teeth 100 between the pinions 34 and 35 and between the racks 36 and 37. After the brakes have been set they are held in this position by the automatic locking of the differential mechanism. Assuming that the ratio of 105 movement between the two sections 11 and 12 of the shaft are as 4 to 1 when the shaft 110 12 tends to move counterclockwise, it will carry the spider 28 with it, which movement through the operation of the differential gear mechanism will tend to cause the casing 23 to move counterclockwise at four times the speed of the spider 28, but the pawl 43 which is mounted on said spider will engage the 115 ratchet teeth on the disk 38 and lock the two sections of the staff together, thereby tending to cause the casing 23 to rotate at four times the rate of speed of the shaft. This relative movement between the shaft and casing, however, is prevented by the pawl 46 on the casing, which engages ratchet teeth on the disk 44 on the shaft, consequently the parts are 120 automatically locked in adjusted position.

Suitable means are provided for releasing the pawl 43 to permit the release of the 125 brakes. Any suitable means may be employed for this purpose. As shown, a lever 47 is pivoted in the hub 27 of the lower casing 24. The lever is provided with arms 48 which are adapted to be turned upwardly through 130

slots 49, see Fig. 2, in the bottom of the lower casing. The disk member 38 is slidably mounted on the lower end of the staff section 11 and is adapted to be supported by a plate 51 slidably mounted on the lower end of said shaft and having leg portions 52 which extend downwardly through suitable openings in the spider 28 and engage a disk 53 which is adapted to be engaged by the arms 48 to raise and lower the same. When the arms 48 are turned in their upward position as shown in Fig. 3 the disk 38 is elevated so that the ratchet teeth are in engagement with the pawl 43. When the arms 48 are turned to the dotted line position shown in Fig. 3 the disk 38 is lowered into the depression in the spider 28 and the pawl 43 which extends across said depression will be held out of engagement with the ratchet teeth on said disk. In other words, when it is desired to release the brake the lever 47 is moved so that the arms 48 will permit the disk 38 to slide downwardly on the lower end of the shaft 11 into the depression in the spider 28 out of engagement with the pawl 43.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:—

1. A brake staff comprising an upper section, a lower section, and differential gear mechanism connecting said sections, said mechanism including a housing comprising a lower section rigidly connected to a support, an upper section rotatably mounted relatively to said staff, said sections being provided with circular racks of different radii, a spider rigidly mounted on the lower section of the staff, a pair of gears rigidly connected together, carried by said spider and engaging said racks, a yielding connection between said staff and spider, and a pawl and ratchet connection between said staff and the upper section of the casing.

2. A brake staff comprising an upper section, a lower section, and differential gear mechanism connecting said sections, said mechanism including a housing comprising a lower section rigidly connected to a support, an upper section rotatably mounted relatively to said staff, said sections being provided with circular racks of different radii, a spider rigidly mounted on the lower section of the staff, a pair of gears rigidly connected together, carried by said spider and engaging said racks, a yielding connection between said staff and spider, a pawl and ratchet connection between said staff and the upper section of the casing, and means for disengaging said spider from said staff.

3. In combination, a sectional brake staff comprising an operating section, an operated section, and differential gear mechanism between said sections, said mechanism comprising fixed and movable annular racks, a gear support fixed to said operated section, a gear member journaled on said support, said gear member comprising a pair of gears rigidly connected together and of different diameters for engaging said racks, respectively, and means for preventing rotation of said movable rack in a direction opposite to that of said operating section.

4. In combination, a sectional brake staff comprising an operating section, an operated section, and differential gear mechanism between said sections, said mechanism comprising fixed and movable annular racks, said racks having an unequal number of teeth, a gear support non-rotatably connected to the operated section of said staff, a pair of relatively fixed gears journaled on said support for engaging said racks respectively, and a pawl and ratchet mechanism for preventing said movable rack from rotating contra to that of the operating section of said staff.

5. In combination, a sectional brake staff comprising an operating section and an operated section, and differential gear mechanism between said sections, said mechanism comprising a fixed rack, a movable rack, supports for said racks, a spider member non-rotatably mounted on the operated section of said staff, a plurality of sets of non-rotatably connected gears journaled on said spider member, the gears of each set engaging said racks, respectively, the combined number of teeth of one gear of each set and its cooperating rack being greater than the other gear of said set and its cooperating rack, a pair of ratchet members rotatable with the operating section of said staff and a pawl on the support for said movable rack, and a pawl on said spider member, for engaging said racks.

6. In combination, a sectional brake staff comprising an operating section and an operated section, and differential gear mechanism between said sections, said mechanism comprising a fixed rack, a movable rack, supports for said racks, a spider member non-rotatably mounted on the operated section of said staff, a plurality of sets of non-rotatably connected gears journaled on said spider member, the gears of each set engaging said racks, respectively, the combined number of teeth of one gear of each set and its cooperating rack being greater than the other gear of said set and its cooperating rack, a pair of ratchet members rotatable with the operating section of said staff, a pawl on the support for said movable rack for engaging one of said ratchet members and a weighted pawl on said spider member for engaging the other ratchet member, whereby upon the initial operation of the

brakes both sections of said staff will move together to take up the slack in the brake operating mechanism, and during the application of the brakes the operating section of said staff will move more rapidly than the operated section.

7. In combination, a sectional brake staff comprising an operating section and an operated section, and differential gear mechanism between said sections, said mechanism comprising a fixed rack, a movable rack, supports for said racks, a spider member non-rotatably mounted on the operated section of said staff, a plurality of sets of non-rotatably connected gears journaled on said

spider member, the gears of each set engaging said racks, respectively, the combined number of teeth of one gear of each set and its cooperating rack being greater than the other gear of said set and its cooperating rack, a pair of ratchet members rotatable with the operating section of said staff, a pawl on the support for said movable rack for engaging one of said racks, a pawl movable with said spider member for engaging the other rack, and means for releasing said last named pawl.

In testimony whereof I affix my signature.

PERCY B. CAMP.
